CLAIM

We claim the ornamental design for a low profile vent, as shown and described.

DESCRIPTION

FIG. 1 is a perspective view of a first embodiment of a low profile vent showing our new design.

FIG. 2 is a top view of the low profile vent of FIG. 1.

FIG. 3 is a bottom view of the low profile vent of FIG. 1.

FIG. 4 is a rear elevation view of the low profile vent of FIG. 1.

FIG. 5 is a front elevation view of the low profile vent of FIG. 1.

FIG. 6 is a left side elevation view of the low profile vent of FIG. 1. The right side elevation view of the low profile vent is a mirror image of the left side elevation view.

FIG. 7 is an enlarged view taken from area 7 circumscribed within FIG. 1.

FIG. 8 is a perspective view of a second embodiment of a low profile vent showing our new design.

FIG. 9 is a top view of the low profile vent of FIG. 8.

FIG. 10 is a bottom view of the low profile vent of FIG. 8.

FIG. 11 is a rear elevation view of the low profile vent of FIG. 8.

FIG. 12 is a front elevation view of the low profile vent of FIG. 8; and,

FIG. 13 is a left side elevation view of the low profile vent of FIG. 8. The right side elevation view of the low profile vent is a mirror image of the left side elevation view.

The ornamental portions of a fibrous filter are visible through the vent openings in the first embodiment of FIGS. 1-7. Undisclosed surfaces of the fibrous filter not visible through the vent openings form no part of the claimed design.

The evenly spaced broken lines and the areas within them in the drawings depict portions of the low profile vent that form no part of the claimed design.

The dot-dash-dot broken lines in FIGS. 1 and 7 denote the boundaries of the enlargement that form no part of the claimed design.

The dot-dot-dash broken line in FIGS. 3 and 10 denotes the boundary of the claim that forms no part thereof.

1 Claim, 11 Drawing Sheets
